UNITED STATES PATENT OFFICE.

WILLIAM JOHN KENNEY, OF WILMETTE, ILLINOIS, ASSIGNEE TO UNDERFEED STOKER COMPANY OF AMERICA, OF CHICAGO, ILLINOIS, A CORPORATION OF NEW JERSEY.

FURNACE.

1,114,269.

Specification of Letters Patent.

Patented Oct. 20, 1914.

Application filed March 13, 1911. Serial No. 614,056.

To all whom it may concern:

Be it known that I, WILLIAM J. KENNEY, a citizen of the United States, residing at Wilmette, county of Cook, State of Illinois, have invented a certain new and useful Improvement in Furnaces, and declare the following to be a full, clear, and exact description of the same, such as will enable others skilled in the art to which it pertains to make and use the same, reference being had to the accompanying drawings, which form a part of this specification.

My invention relates to furnaces and more particularly to automatic stoking mechanism and has, for its primary object, to provide means for effectively clearing the furnace of clinkers and ashes without wasting unconsumed fuel.

The various features of novelty whereby my invention is characterized will herein-after be pointed out with particularity in the claims; but for a full understanding of my invention and its various objects and advantages, reference may be had to the following detailed description taken in connection with the accompanying drawings, wherein:

Figure 1 is a longitudinal vertical section taken through a furnace arranged in accordance with a preferred form of my invention; Fig. 2 is a transverse vertical section through the furnace; Fig. 3 is a horizontal section taken directly above the retort, the dead-plates at one side of the retort being omitted for the purpose of showing the underlying parts; Fig. 4 is a side elevation of the cleaning mechanism detached from the furnace, the parts occupying different positions from those indicated in Fig. 1; Fig. 5 is a side view on an enlarged scale of the detachable driving connection for the dumping mechanism; and Fig. 6 is a section on line 6—6 of Fig. 5.

In the drawings, I have illustrated my invention as applied to an automatic under-feed stoker of the type disclosed in the Kenney and Grohn application, Serial No. 457,199, filed October 12, 1908; and, for the sake of brevity, I shall refer only to this specific embodiment in the detailed description; but I desire to have it understood that I do not limit myself to any particular construction and arrangement of furnace, except as particularly pointed out by the

terms employed in the definitions of my invention, constituting the appended claims.

Referring to the drawings, 1 designates a furnace of any suitable or usual construction. Extending longitudinally along the center of the furnace is a retort 2. The retort is shorter than the furnace so as to leave room for the mouth of an outlet passage 3 between the rear end of the retort and the rear wall of the furnace. Below the discharge passage is an ash chute 4. Fuel is supplied to the retort by means of suitable charging mechanism 5. Between the sides of the retort and the side walls of the furnace, are dead-plates 6 and 7.

In accordance with one feature of my invention, I mount upon the dead-plates several longitudinal series of blocks or dogs 8, which lie within openings 9 in the dead-plates and are pivotally supported in such a manner that they may be swung from a position wherein they lie below the top surfaces of the dead-plates into a position wherein portions thereof project above the dead-plates. The noses of the dogs, 10, which are adapted to project above the dead-plates, are arranged in front of the pivots 11, so that when the dogs are oscillated, the noses move upwardly and also rearwardly. By this construction, the clinkers are broken up, and the clinkers and ashes are fed toward the rear of the furnace and are discharged into the passage 3. The dogs may be actuated in any suitable manner. In the arrangement shown, each series of dogs—that is, each row extending longitudinally of the furnace—is connected together by a rod or link 12. A horizontal actuating shaft 13 passes transversely through the furnace beneath the retort and is oscillated by means of a suitable power device 14. The links 12 are connected to crank-arms 15 and 16, rigidly secured to the shaft 13. Consequently, as the shaft is oscillated, the members 12 are reciprocated and the dogs are oscillated about their pivots, alternately rising above and dropping below the upper surfaces of the dead-plates.

In accordance with the second feature of my invention, I provide means for controlling the final discharge of the clinkers and ashes. In the preferred arrangement, I mount a movable perforated supporting

- plate 17 across the lower end of the passage 3. When the supporting plate is in the position indicated in Fig. 1, the clinkers and ashes may pile up thereon, free air passing up through the perforations and completing the combustion of any small quantities of partially consumed fuel which may have been discharged from the retort and dead-plates.
- 10 I prefer to make the passage 3 quite long so as to bring the supporting plate considerably below the surface of the fuel-supporting bed; thus leaving room for a substantial column of clinkers and ashes ready to drop 15 into the receiving chute. In connection with the long outlet passage I sometimes prefer to use means for discharging the column of clinkers and ashes a little at a time, thus causing the clinkers and ashes to descend gradually and rest directly on the perforated supporting plate before being 20 finally discharged. To this end I associate with the supporting plate a discharging trough or receptacle 18, this lying below the 25 supporting plate and having one of its side edges joined to one edge of the plate. The combined supporting and dumping member is mounted on a horizontal shaft 19 extending along the bottom of the trough. When 30 the parts are in the position shown in Fig. 1, the trough is in its dumping position so that any matter which may have been contained therein will have dropped into the discharge chute. When the shaft is oscillated in the 35 counter-clockwise direction, as viewed in Fig. 1, the supporting plate passes forwardly out of the passage 3 and the trough 18 takes its place across the passage. The clinkers and ashes contained in the passage 40 now drop into the trough and, by returning the parts to the positions indicated in Fig. 1, a section of the column of clinkers and ashes, lying in the passage 3, is cut from the lower end thereof and is dumped into the 45 discharge chute. By this arrangement, the passage 3, when full, will not be emptied by a single operation of the dumping mechanism, but will require several operations. Consequently, any small quantities of un- 50 consumed fuel within the passage are always given the chance to lie, for a time, upon the perforated supporting plate and be consumed by air passing upwardly through the perforations.
- 55 The dumping mechanism may be actuated in any suitable way, manually or by power, it being only necessary to oscillate the shaft 19 on which the dumping devices are mounted. In the arrangement illustrated, I have 60 shown means for operating the dumping mechanism by power when and as desired. To this end I provide the shaft 19 with a crank arm 20 at one end, a connecting rod 21 extending forward from the crank arm to 65 a point in proximity to the outer end of an

arm 22 fixed to the main shaft 13. On the arm 22 is a pin 23 and on the under side of the connecting rod is a notch 24 adapted to receive the pin. When the connecting rod is dropped until the pin 23 is received in the notch 24, a driving connection is afforded between the dumping mechanism and the main shaft 13; the dumping mechanism oscillating in unison with the dogs 8 in the dead plates. When the connecting rod is lifted, freeing it from the pin 23, the driving connection between the main shaft and the dumping mechanism is interrupted and the dumping mechanism remains stationary. Consequently the dumping mechanism may be actuated whenever desired and for any desired length of time, remaining stationary at other times and allowing the clinkers and ashes to pile up on the supporting plate. For controlling the connecting rod 21 I have provided a rock shaft 25 pivoted to a fixed support adjacent to the connecting rod and having an arm 26 underlying the same. In one position of the rock shaft it holds the connecting rod raised 80 clear of the pin 23, while in its other position it allows the connecting rod to drop far enough to bring the notch 24 over the pin and thus complete the driving connection for the dumping mechanism.

It will be seen that the retort and the dead plates divide the furnace into an upper combustion chamber and a lower air chamber. Air is introduced into the air chamber through a suitable blower 27 and passes up 100 through the usual twyer blocks 28 placed around the upper edge of the retort. The fuel is fed into the retort, burning in the liberating zone at the top of the retort, and being discharged upon the dead plates in the 105 form of clinker and ash containing some unconsumed fuel. As the dogs 8 are oscillated, the clinkers are broken up and broken away from the twyer blocks, and the whole mass is gradually fed toward the rear end of the 110 furnace. When the clinkers and ashes reach the rear end of the furnace they drop into the discharge passage and upon the perforated supporting plate, forming a column of hot material which will continue to burn 115 in the air supplied from below if there happens to be any combustible matter left among the clinkers and ashes. The dead plates are practically imperforate except for the small passages around the oscillatory dogs. Consequently the incoming air extracts heat from the dead plates, raising its own temperature and keeping the dead plates comparatively cool; so that the air passing into the combustion chamber through the twyer 125 blocks is already warm and improves the combustion.

The driving means for the mechanism which moves the clinkers and ashes toward the rear of the furnace may be regulated so 130

as to produce any desired speed of travel in the moving mass, while the dumping or discharging mechanism which makes the final disposition of the clinkers and ashes may be controlled independently of the other mechanism so as not to be required to operate according to any fixed constant determined by the other mechanism.

It will thus be seen that I have produced a simple and efficient mechanism for positively clearing a furnace of clinkers and ashes, sufficient flexibility of operation being afforded to insure the attainment of the best working condition in all cases.

15 I claim:

1. In combination, a furnace, a retort within the furnace, stationary dead plates arranged at the sides of the retort and with the latter dividing the furnace into an upper combustion chamber and a lower air chamber, dogs mounted on said dead plates and adapted to move upwardly and rearwardly, means for actuating said dogs, means for delivering fuel to the retort, and means for introducing air into the air chamber, there being passages from the air chamber to the combustion chamber at the sides of the retort.

2. In combination in a stoker, a retort, twyer blocks arranged around the top of the retort, stationary dead plates arranged about the retort outside of the twyer blocks near the top of the retort, means for feeding fuel into said retort, dogs mounted on said dead plates and adapted to move upwardly and rearwardly to carry the clinkers and ashes toward the rear of the retort, and means for actuating said dogs.

3. In combination, a furnace, a retort within the furnace, stationary dead plates arranged at the sides of the retort and coöperating therewith to divide the furnace into an upper combustion chamber and a lower air chamber, there being a discharge passage for clinkers and ashes at one end of the retort, dogs mounted on said dead plates and movable upwardly and longitudinally to carry the clinkers and ashes toward said passage, means for actuating said dogs, means for delivering fuel to the retort, and means for admitting air into said air chamber, there being passages leading from said air chamber to the combustion chamber at the sides of the retort.

4. In combination, a furnace, a retort with-

in the furnace, means between the sides of the retort and the side walls of the furnace for moving clinkers and ashes toward one end of the furnace, there being a discharge passage for clinkers and ashes adjacent to the retort at said end of the furnace, said means forming with the retort a member dividing the furnace into an upper combustion chamber and a lower air chamber, there being passages leading from said air chamber to the combustion chamber at the sides of the retort, means for introducing air under pressure into said air chamber, and means located in said passage at a considerable distance below the top of the retort for periodically removing only the lowermost portion of the clinkers and ashes in said passage, the last mentioned means being perforated to permit air to flow up through the body of clinkers and ashes in said passage.

5. In combination, a furnace, a retort within the furnace, stationary dead plates arranged at the sides of the retort and coöperating therewith to divide the furnace into an upper combustion chamber and a lower air chamber, there being a discharge passage for clinkers and ashes in the furnace adjacent to one end of the retort, dogs mounted on said dead plates so as to be movable upwardly and longitudinally of the retort so as to move the clinkers and ashes toward said passage, a dumping plate extending across said passage, a common operating means for said dogs and said plate, means for delivering fuel to the retort, and means for delivering air into said chamber.

6. In combination in a stoker, a retort, stationary dead plates arranged at the sides of the retort for receiving clinkers and ashes therefrom, movable dogs mounted on said dead plates for carrying the clinkers and ashes toward one end of the retort, a rock shaft extending transversely beneath the retort and the dead plates, a connection between said rock shaft and said dogs, a power device for actuating said rock shaft, and an independent power device for delivering fuel to the retort.

In testimony whereof, I sign this specification in the presence of two witnesses.

WILLIAM JOHN KENNEY.
